(57) CLAIM

The ornamental design for a desk organizer as shown and described.

DESCRIPTION

FIG. 1 is a front perspective view of a desk organizer showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a front perspective view showing the desk organizer with a drawer;

FIG. 11 is a rear perspective view thereof; and,

FIG. 12 is a bottom perspective view thereof.

The broken line portions of the desk organizer in FIGS. 1-12 represent unclaimed portions of the claimed design and form no part thereof. The broken lines of the drawer in FIGS. 10-12 illustrate unclaimed environment and forms no part of the claimed design.

1 Claim, 10 Drawing Sheets
